(57) **CLAIM**

(51) **LOC (11) Cl.** **12-16**

The ornamental design for a tire sidewall, as shown and described.

(52) **U.S. Cl.**

USPC **D12/605**

DESCRIPTION

(58) **Field of Classification Search**

FIG. 1 is a perspective view of a tire sidewall showing my design;

USPC D12/605, 500-501, 506, 434-538,
D12/569-573, 604, 900, 202, 502-505,
D12/507-533, 539-568, 574-603;
D5/30; D7/396.4, 396.5

FIG. 2 is a front view thereof;

CPC B60C 13/00; B60C 1/00
See application file for complete search history.

FIG. 3 is a top view thereof;

(56) **References Cited**

FIG. 4 is a right side view thereof;

U.S. PATENT DOCUMENTS

FIG. 5 is a rear view thereof;

D769,807 S * 10/2016 Ishikawa D12/605
D773,985 S * 12/2016 Sakamoto D12/605

FIG. 6 is a fragmentary enlarged front view surrounded by line 6 in FIG. 2, showing the details of the tire sidewall thereof;

(Continued)

FIG. 7 is an enlarged section view taken along line 7-7 in FIG. 6,

FIG. 8 is a fragmentary enlarged front view surrounded by line 8 in FIG. 2, showing the details of the tire sidewall thereof; and,

FIG. 9 is an enlarged section view taken along line 9-9 in FIG. 8.

Broken lines are provided to show portions of the tire that are not being claimed, and thus form no part of the claimed design.
